2,462,529

HORIZONTAL OIL BURNER OF THE
TRAY TYPE

Clarence A. Miller, Petaluma, Calif., assignor to
Kresky Mfg. Co., Inc., Petaluma, Calif., a corporation of California

Application July 23, 1945, Serial No. 606,559

4 Claims. (Cl. 158—91)

1

This invention relates to liquid fuel burners, and particularly to oil burners of the vaporizing type for domestic and industrial use employing a gravity feed and from which the flame is projected in a horizontal rather than a vertical direction.

In the past, oil burners of this type have been subject to the excessive formation of carbon which ultimately effectively closed the orifices through which air is introduced into the combustion chamber. Furthermore, the creation of carbon upon the walls of the combustion chamber results in irregularities of the flow of air therethrough and the creation of turbulence which results in inefficient operation and incomplete consumption of the combustible vapors.

It is an object of the present invention to provide an oil burner of this type, in which the air is introduced into the combustion chamber in such a manner that complete combustion of all of the hydrocarbon fractions adjacent to the walls of the chamber is obtained, with the resultant elimination of carbon deposits upon the walls.

Another object of this invention is to provide a burner of this type which produces an effective horizontal flame with the maximum effective combustion of the hydrocarbon fractions at a point remote from the flame throat or outlet.

Other objects of this invention will appear from the following description, in which the preferred embodiment of the invention is disclosed in conjunction with the accompanying drawings, in which:

Figure 1 is a plan view of an oil burner unit embodying the present invention.

Figure 2 is a side elevational view of the oil burner unit shown in Figure 1.

Figure 3 is an enlarged longitudinal sectional view of the burner element incorporated in the burner unit, taken along the line 3—3 in Figure 4.

Figure 4 is a plan view of the lower casing section of the burner element.

Figure 5 is a lateral sectional view of the lower casing section, taken along the line 5—5 in Figure 4.

Figure 6 is a top view of the upper casing section of the burner element.

Figure 7 is a rear view of the upper casing section.

Figure 8 is a front view of the upper casing section.

Figure 9 is a side view of the upper casing section.

Figure 10 is a bottom view of the upper casing section.

Referring now more particularly to Figures 1 and 2, there is shown an oil burner unit 10 embodying the features of the present invention and comprising a supporting plate 11, carrying

2

an oil burner housing 12 disposed on one side thereof and a motor operated fan 13 and associated oil supply regulator 14 disposed on the opposite side thereof. The burner housing 12 comprises wall structure, including a front wall 15, defining a housing for a burner element 20 disposed therein. The fan 13 is operative to supply air under pressure into the housing 12, which air is utilized by the burner element 20 in a manner more fully described hereinafter; while the regulator 14 is connected to a source of oil or other liquid fuel, not shown, and is operative to supply a regulated quantity of the oil to the burner element 20. The burner unit 10 is adapted to be supported in cooperative relation with a stove, range, or the like, the housing 12 projecting into the firebox of the stove and the fan 13 and the regulator 14 being disposed exteriorly thereof.

As best shown in Figures 3 to 10 inclusive, the burner element 20 essentially comprises upper and lower casing sections 21 and 22 respectively, which are preferably cast from iron or the like. The two casings 21 and 22 are fitted together, as shown in Figure 3, and maintained in predetermined relationship by bolts or the like, not shown, which cooperate with holes 21a and 22a respectively formed therein. The two casings 21 and 22, thus assembled, define a combustion chamber 23, terminating in a rectangular throat 24 projecting through a cooperating opening formed in the front wall 15 of the housing 12. The casing 22 is provided with a depending well 25, into which oil is adapted to be fed from the regulator 14 in any suitable manner, as for example, by means of gravity. It is contemplated that in an average installation the oil will substantially fill the well 25 and at times form a thin layer in the bottom of an adjacent cavity 26.

The casing 22 is provided with upstanding walls 27, 28 and 29, which are spaced from corresponding walls 30, 31 and 32 of casing 21. At its forward end casing 22 is provided with a sloping wall 33, as shown, the forward lip 34 of which forms the lower lip of the flame-ejecting throat 24. The forward edges of walls 30 and 32, together with the forward lip of an upper wall 35 of casing 21, constitute the other lips of the flame throat 24.

I have provided various orifices in the walls 30, 31, 32 and 35 of casing 21. Specifically, I have provided three rows of small orifices 31a in wall 31 of casing 21, which orifices I refer to as "primary" orifices in that they serve to admit air for "primary" combustion. Similar "primary" orifices 30a and 32a are provided in side walls 30 and 32, respectively, adjacent to the lower edges thereof, substantially as shown. The purpose of the primary orifices is to provide heated air and oxygen to the hot saturated vapors in the generally centrally located area within the combustion

chamber 23. I do not propose that these orifices admit sufficient air to provide complete combustion, it being the purpose of this air to permit a slight degree of combustion and allow the generation of a small degree of heat. I do not wish the complete combustion of the hot vaporized gases to occur in this area because such combustion would create a substantial quantity of carbon dioxide, resulting in the dampening of further combustion in the forward portion of the combustion chamber 23.

It will be appreciated that the walls of the combustion chamber 23 will absorb considerable heat. I have found, for example, that in a small burner element 20 adaptable for use upon an ordinary kitchen range, the combustion chamber 23 of which is approximately four inches square and two inches deep with the consumption of 32 cc. of oil per minute, the walls will, within six or seven minutes after the commencement of operation of the device, acquire a temperature of approximately 700° F. This heat, when transmitted to the well 25 and cavity 26, will result in the vaporization of the oil therein and create a substantial vapor pressure moving directly upwardly toward wall 35. The introduction of primary air through the primary orifices 30a, 31a and 32a will institute combustion and direct the flow of saturated vapors generally toward the flame throat 24. It will be appreciated that the air forced through orifices 30a, 31a and 32a will have passed between walls 27 and 30, 28 and 31, and 29 and 32 and will have acquired considerable heat therefrom, thereby adding to the combustibility of the mixture.

I have provided larger orifices 31b in wall 31 near the upper and side boundaries thereof, substantially as shown. Similar orifices 30b and 32b are provided along the forward sloping edges of walls 30 and 32, respectively. I have provided a like row of secondary orifices 35b for the admission of secondary air through wall 35 at a point immediately to the rear of the forward edge thereof. The purpose of orifices 31b in the end wall 31 is to provide secondary air for the first stages of complete combustion within the combustion chamber 23. Furthermore, air forced into the combustion chamber 23 through these orifices gives the heated gases their final direction and creates a thin boundary layer of complete combustion along walls 30, 32 and 35. The introduction of substantial quantities of air through these orifices will thereby create a cushion of completely burned gases immediately adjacent to the upper and side walls of the combustion chamber 23 and prevent the formation of carbon thereon. The secondary orifices 30b and 32b are adapted to provide a layer of air immediately adjacent to the upper surface of sloping wall 33. The air introduced into the combustion chamber through these orifices is adapted to mix with the rich gases moving forwardly immediately over the oil pool in the well 25 below the combustion chamber 23 and to form a boundary layer of completely burned gases immediately adjacent to wall 33, whereby the formation of carbon thereon is prevented. The introduction of high velocity air through the orifices 35b is adapted to provide sufficient air for the complete combustion of the gases beyond the lips of the flame throat 24.

It will be noted that the primary air passes between the vertical walls of the lower casing 22 and the vertical walls of the upper casing 21 before passing through orifices 30a, 31a and 32a. It will be seen that the primary air entering the

combustion chamber 23 does so at a higher temperature than the secondary air entering the combustion chamber 23 which has not passed between the vertical walls but acquires its heat solely by the passage through the orifices 30b, 31b and 32b in the vertical walls of casing 21.

It will be appreciated that air will be supplied under pressure by the fan 13, and will be conducted to the burner element 20 from the surrounding housing 12. As has previously been pointed out, all the walls of the burner element 20 are heated to an elevated temperature and the air passed thereover and therethrough is likewise heated. The elevated temperature of the secondary air forced through the orifices 30b, 31b and 32b aids in the combustion of the saturated vapors which have previously been mixed with the primary air introduced through orifices 30a, 31a and 32a.

It is essential that the introduction of secondary air be restricted inasmuch as too great a quantity thereof would result in complete combustion within the combustion chamber 23. It is desired that complete combustion and maximum temperature occur at a point beyond the lips of the flame throat 24.

It will be noted that in the design shown herein, the surface of the oil within the pool created in well 25 and cavity 26 occupies a relatively small area in the base of casing 22. As the casing 22 assumes considerable heat, this oil vaporizes and the gases expand throughout the combustion chamber 23. By the introduction of primary and secondary air into the upwardly moving hot, saturated vapors in a predetermined manner, I can control the point of complete combustion of these gases.

The operation of the oil burner unit 10 may, briefly, be described as follows: The burner element 20 is connected to a suitable supply of oil which is fed thereto from the regulator 14 by gravity or in any conventional manner, it being essential only that oil be continually supplied to the burner element 20 and that the same be maintained at substantially a predetermined level which, as shown, is substantially that of the lower surface of cavity 26. Air is fed to the burner element 20 from the housing 12, which is supplied by the fan 13. When the burner unit 20 and the oil in well 25 are cold, the same may be lighted in any conventional manner. As combustion starts, the walls of the combustion chamber 23 gradually become heated. As has been previously pointed out, after a short period of operation the walls reach a temperature of approximately 700° F. A portion of the heat is transmitted to the oil in well 25 and to the air entering the combustion chamber 23 through the various orifices. Heating of the oil in well 25 and cavity 26 results in the production of a substantial quantity of hot, saturated gas moving toward wall 35. The introduction of primary heated air through orifices 31a starts the vapors moving forwardly and results in incomplete combustion. The introduction of primary air at a point immediately over the upper surface of the oil pool in this manner prevents the creation of turbulence immediately over the oil pool.

The introduction of secondary air through orifices 30b, 31b, 32b and 35b forces the combustible gases forwardly through the throat 24. The amount of secondary air is predetermined to provide sufficient air for complete combustion of most of the gases beyond throat 24 but not within the combustion chamber 23. The introduction

of secondary air immediately adjacent to the walls 30, 31, 32 and 33 provides a skin layer or boundary layer of completely burned gases which provide a suitable preventive cushion adjacent to these walls to prevent the formation of carbon thereon.

My experiments have disclosed that the introduction of the proper amount of primary air is critical. The introduction of an excessive quantity of primary air is apt to result in the complete combustion of the hot saturated gases arising from the pool of oil which, in turn, results in the creation of substantial quantities of carbon dioxide and dampening of further combustion within the combustion chamber 23. The introduction of too little primary air would result in the generation of insufficient heat to heat the bottom casing 22 to the proper temperature to vaporize the oil in the pool or well 25. Also the introduction of too little primary air does not permit sufficient combustion of the gases in the central zone of the combustion chamber 23 and results in incomplete combustion of the gases along the walls of the same, regardless of the quantity of secondary air introduced. Incomplete combustion adjacent to the walls results in the creation of carbon; introduction of too little primary air does not create a forward movement of the mass of combustible vapors within the combustion chamber 23, with the result that when the gases mix with the secondary air excessive turbulence is created, thereby decreasing the efficient combustion of the mass.

Further experiments have shown that the introduction of too little secondary air results in incomplete combustion immediately adjacent to the walls of the combustion chamber 23 and permits the creation of carbon thereon. Introduction of too much secondary air through the orifices in the rear of wall 31 of casing 21 results in complete combustion of all of the gases within the combustion chamber 23 instead of at a point beyond the throat 24.

By way of illustration, I have provided a combustion chamber 23 substantially 4 inches wide, 4½ inches long, and substantially 2¼ inches deep. Primary air is introduced through thirty orifices 31a, each of which is ¼ inch in diameter, in the rear wall 31, and five orifices 30a and 32a of the same diameter in each of the respective side walls 30 and 32. The rear-most of these orifices 30a and 32a in the side walls 30 and 32 is in the same vertical plane as the forward wall of well 25. The lowermost of these orifices 31a in the rear wall 31 is approximately ⅜ of an inch above the upper surface of the oil within well 25, while the uppermost is approximately 1¼ inches above that surface. It will be seen that a primary zone approximately 1¼ inches high is created within the combustion chamber 23, or, in other words, that substantially the entire lower half thereof constitutes a primary combustion zone. The primary air entering the combustion chamber 23 through these orifices 30a, 31a and 32a results in incomplete combustion of the gases within this zone and changes the course of the heated vapor from a vertical to a substantially horizontal course.

Secondary air is provided for the combustion chamber 23 through twenty-one orifices 31b, each of which is approximately ⅛ of an inch in diameter, adjacent to the lower surface of wall 31 and by the provision of two more groups of three orifices 31b of the same diameter in the wall 31 respectively adjacent to the inner surface of walls 30 and 32. Introduction of secondary air through these orifices 31b creates a zone of com-

plete combustion immediately adjacent to these walls, with a zone of incomplete combustion between said zone and the primary zone, and further aids in the forcing of the gases in a forward direction.

Secondary air is further provided through three orifices 30b and 32b of the same diameter in each of the respective walls 30 and 32 immediately adjacent to the sloping wall 33. Secondary air introduced there further supplies air for a zone of combustion immediately adjacent to the sloping wall 33 and for complete combustion at a point beyond the throat 24. Further, secondary air is provided by sixteen orifices 35b of the same size in wall 35 immediately adjacent to the throat 24. The air introduced at this point is calculated to be sufficient to result in complete combustion of the gases at a point beyond the throat 24.

It will be appreciated that the number and size of the orifices may be varied for different sizes of combustion chambers. However, I have found that it is desirable to provide a lower zone of primary combustion and a surrounding zone of secondary combustion, which latter zone is likewise divided into a zone of complete combustion immediately adjacent to the walls of the chamber and a second zone of incomplete combustion to which further secondary air is added immediately adjacent to the throat 24 in order that complete combustion of all of the gases will occur at a point beyond the combustion chamber 23.

While there has been described what is at present considered to be the preferred embodiment of the invention, it will be understood that various modifications may be made therein and it is intended to cover in the appended claims all such modifications as fall within the true spirit and scope of the invention.

What is claimed is:

40. 1. A burner comprising upper and lower casing sections secured together and defining a combustion chamber, said upper casing section including a top wall and a connecting downwardly extending first skirt having an opening in the front portion thereof, said lower casing section including a bottom wall having a depression formed therein defining a liquid fuel reservoir disposed below and directly communicating with said combustion chamber and an upwardly sloping front wall and a connecting upwardly extending second skirt, said first skirt extending above and having its lower part arranged within said second skirt in spaced relation thereto, the front edge of said top wall and the front edges of said first skirt adjacent to the opening in the front portion thereof cooperating with the front edge of said front wall to define a forwardly directed flame outlet throat, means for supplying liquid fuel to said reservoir, said first skirt having a number of air inlet openings formed therein and disposed above and below the upper edge of said second skirt, and means for directing air from the exterior of said casing sections through said openings and across said reservoir, whereby vaporized fuel from said reservoir and flames of burning fuel in said combustion chamber are projected forwardly through said flame throat to the exterior of said casing sections.
45. 2. A burner comprising upper and lower casing sections secured together and defining a combustion chamber, said upper casing section including a top wall and a connecting downwardly extending first skirt having an opening in the front por-

tion thereof, said lower casing section including a bottom wall having a depression formed therein defining a liquid fuel reservoir disposed below and directly communicating with said combustion chamber and an upwardly sloping front wall and a connecting upwardly extending second skirt, said first skirt extending above and having its lower part arranged within said second skirt in spaced relation thereto, the front edge of said top wall and the front edges of said first skirt adjacent to the opening in the front portion thereof cooperating with the front edge of said front wall to define a forwardly directed flame outlet throat, means for supplying liquid fuel to said reservoir, said first skirt having primary and secondary air inlet openings formed therein and respectively disposed below and above the upper edge of said second skirt and said top wall having secondary air inlet openings formed therein adjacent to the front edge thereof, and means for directing air from the exterior of said casing sections into said primary air inlet openings and into said secondary air inlet openings, the air directed into said primary openings sweeping across said reservoir, whereby vaporized fuel from said reservoir partially burned in said combustion chamber, the air directed into said secondary openings entering directly into said combustion chamber whereby vaporized fuel is further burned therein and flames of burning fuel in said combustion chamber are projected forwardly therefrom through said flame throat to the exterior of said casing sections in order to burn completely the vaporized fuel exteriorly of said casing sections.

3. A burner comprising a housing, upper and lower casing sections arranged within said housing and secured together and defining a combustion chamber, said upper casing section including a top wall and a connecting downwardly extending first skirt having an opening in the front portion thereof, said lower casing section including a bottom wall having a depression formed therein defining a liquid fuel reservoir disposed below and directly communicating with said combustion chamber and a front wall and a connecting upwardly extending second skirt, said first skirt extending above and having its lower part arranged within said second skirt in spaced relation thereto, the front edge of said top wall and the front edges of said first skirt adjacent to the opening in the front portion thereof cooperating with the front edge of said front wall to define a forwardly directed flame outlet throat, means for supplying liquid fuel to said reservoir, said first skirt having a number of air inlet openings

formed therein and disposed above and below the upper edge of said second skirt, and means for supplying air into said housing, whereby air is directed from within said housing through said air inlet openings and across said reservoir, whereby vaporized fuel from said reservoir and flames of burning fuel in said combustion chamber are projected forwardly through said flame throat to the exterior of said housing.

4. A burner adapted to project a flame horizontally therefrom comprising upper and lower casing sections secured together and defining a combustion chamber, said upper casing section including a top wall and a connecting downwardly extending first skirt having an opening in the front portion thereof, said lower casing section including a bottom wall and a connecting upwardly extending second skirt, said first skirt extending above and having its lower part arranged within said second skirt in spaced relation thereto, the front edge of said top wall and the front edges of said first skirt adjacent to the opening in the front portion thereof cooperating with the front edges of said second skirt and bottom wall of said lower casing section to define a forwardly directed flame outlet throat, means to supply liquid fuel to said bottom wall of said lower casing, said first skirt having a number of air inlet openings formed therein and arranged above and below the upper edge of said second skirt, and means for directing air from the exterior of said casing sections through said air inlet openings and into said combustion chamber whereby vaporized fuel and flames of burning fuel in said chamber are projected forwardly through said flame throat to the exterior of said casing sections.
